UNITED STATES PATENT OFFICE.

JUSTUS B. ENTZ, OF CLEVELAND, OHIO.

STARTER.

1,052,575.

Specification of Letters Patent. Patented Feb. 11, 1913.

Application filed April 20, 1912. Serial No. 692,159.

To all whom it may concern:

Be it known that I, JUSTUS B. ENTZ, a citizen of the United States, residing at Cleveland, in the county of Cuyahoga and State of Ohio, have invented a certain new and useful Improvement in Starters, of which the following is a full, clear, and exact description.

This invention relates to improvements in starters for internal combustion engines, and has for its main object the provision of means for minimizing liability of premature ignition in a cylinder, that is ignition prior to the time that the piston reaches the end of its compression stroke, while the engine is being turned over by the starter.

A further object is to provide means which prevent the operator stopping the engine when the controlling switch of an electric starting and lighting system, including a dynamo motor, is closed.

Ignition systems for internal combustion engines, especially those employed in motor vehicles usually include a magneto having associated therewith a mechanically operated circuit breaker which periodically closes and opens the magneto circuit, and a magneto switch by which the magneto may be cut into or out of service. This switch, when closed, short circuits the magneto, and as long as it is closed renders the circuit breaker ineffective, but when it is opened, the magneto circuit may be periodically opened and closed by the circuit breaker. In case, however, this switch after being closed, is opened at the time that the circuit breaker is open, there occurs in the magneto armature practically the same magnetic and electrical effects that normally occur on the opening of the circuit breaker. It is customary also at the present time to start internal combustion engines by starting motors of electric or other types which turn over the engine until ignition takes place in the cylinders, and the engine is operated under its own power. Ordinarily when the engine is being turned over, the spark is retarded so that the igniting arc is not created in the cylinder until after the piston has completed its compression stroke. When the spark is retarded by the adjustment of the circuit breaker, premature ignition prior to the time that the piston reaches the end of its compression stroke, cannot take place

turbed. It has been found, however, that when the spark is retarded and the engine is being turned over by the starter if the magneto switch is closed and opened by hand, as might be done by a more or less inexperienced operator, it is possible to open the switch, and hence the magneto circuit prior to the time that the circuit would normally be opened by the circuit breaker, and at such a time in the cycle of the generated wave, that premature ignition may take place. If this occurs, the engine is liable to start backward and serious damage will result.

By my present invention, the liability of premature ignition under the above mentioned circumstances is eliminated by the provision of means for rendering impossible the opening and closing of the ignition circuit independently of the circuit breaker or by the opening and closing of the ignition controlling switch during the time that the engine is being turned over by the starter.

When my invention is employed in connection with a starting and lighting system including a dynamo motor or dynamo electric machine, which is to serve both as a motor for starting purposes, and as a generator for lighting and battery charging purposes, as herein shown and described, it is impossible for the operator to stop the engine by short circuiting the magneto without opening the starter switch, that is without disconnecting the battery and dynamo motor.

My invention may be briefly summarized as consisting in certain novel combinations and arrangements of parts which will be described in the specification and set forth in the appended claims.

The single figure of the drawings shows diagrammatically a combined starting and a portion of an ignition system equipped with one form of my invention.

Although it is immaterial as far as the broad features of my invention are concerned, the particular type of starter and the particular type of ignition system which are employed, I have, however, in the drawing illustrated an electric starter, as my invention is of particular utility in connection with a starter of this type, and I have here shown a so-called high tension magneto, the latter being shown for convenience of illustration only.

In the drawing I have shown at 10 a portion of the crank shaft of the engine, which is designed to be started by a dynamo electro machine 11, when supplied with current from a battery 12. The dynamo electro machine 11 may serve as a motor to start the engine, and after the engine is started, as a generator to charge the battery 12, or to supply current to the lamps of a lighting circuit 13. The dynamo electro machine, which for convenience and ease of description may be hereinafter referred to as the motor, may be connected to the crank shaft by any sort of driving mechanism, gearing 14 being here shown. The motor and battery are designed to be connected or disconnected by means of a starter controlling switch 15.

At 16 is shown a magneto having in this case a secondary winding 16^a which will be connected in the usual manner to a distributor and spark plugs not shown, and having a primary winding 16^b whose circuit is adapted to be opened and closed periodically in the usual manner by a circuit breaker 17 which is operated by a cam generally mounted on the armature shaft. This circuit breaker, as will be seen from the drawing, short circuits the primary and thence opens the same.

The magneto switch previously referred to is shown at 18. This switch 18 is ordinarily so connected to the winding that when closed, it as effectively short-circuits the magneto as does the circuit breaker, and when opened, opens the circuit of the magneto, if the contacts of the circuit breaker happen to be open or separated. To eliminate the danger of premature ignition by operating this magneto switch at the time the engine is being started or turned over by the motor 11, I provide in series relation with this switch 18, a third switch 19, including in this case a movable switch blade and a pair of terminals, and so provide means whereby the starter controlling device 15 when operated to cause the starter to turn over the engine renders the switch 18 ineffective for closing or opening the magneto circuit. In this case, this is accomplished by connecting the blade of the switch 19 to the switch 18, so that when the switch 15 is closed, the switch 19 will be opened, and when the switch 15 is opened, the switch 18 will be closed.

I do not desire my invention to be limited to any specific details or to any specific forms of the devices employed in carrying out my invention, except so far as I am

expressly limited by the terms of the appended claims.

Having thus described my invention, what I claim is:

1. In combination with an internal combustion engine, a starter therefor, a source of ignition current, a switch for controlling the ignition, and means for rendering said switch ineffective when the engine is being turned over by the starter.

2. In combination with an internal combustion engine, a starter therefor, an operable controlling member for the starter, an ignition circuit, an ignition controlling switch, and means associated with said controlling means for rendering said switch ineffective when the engine is being turned over by the starter.

3. In combination with an internal combustion engine, a starter, an operable controlling member for the starter, a source of ignition current, an ignition controlling switch, and means for having an operative connection with said controlling member for rendering said switch ineffective when said controlling member is operated to cause the starter to turn over the engine.

4. In combination with an internal combustion engine, a starter, an operable controlling member for the starter, a source of ignition current, an ignition controlling switch, and a second switch in series relation with said switch and mechanically connected to the operable member so that said second switch is opened when the operable member is actuated to cause the starter to turn over the engine.

5. In combination with an internal combustion engine, a starting system comprising a motor for turning over the engine, a battery for supplying current to the motor and a starter switch for connecting and disconnecting the battery and motor, igniting means for the engine comprising a magneto, a magneto switch for short circuiting the magneto so as to render it effective or ineffective for ignition purposes, and a third switch in series relation with the magneto switch and connected to the starter switch so that the third switch will be opened when the starter switch is closed and will be closed when the starter switch is opened.

In testimony whereof, I hereunto affix my signature in the presence of two witnesses.

JUSTUS B. ENTZ.
